UNITED STATES PATENT OFFICE.

HERBERT A. THAYER, OF PROVIDENCE, RHODE ISLAND.

NUMBER-PLATE FRAME.

1,412,580.

Specification of Letters Patent. Patented Apr. 11, 1922.

Application filed December 27, 1920. Serial No. 433,342.

To all whom it may concern:

Be it known that I, HERBERT A. THAYER, a citizen of the United States, residing at Providence, in the county of Providence and

5 State of Rhode Island, have invented certain new and useful Improvements in Number-Plate Frames, of which the following is a specification.

This invention relates to improvements in 10 number-plate frames for motor vehicles; and the object of this invention is to provide a metal frame of this character for stiffening the usual sheet metal number plate and to support it firmly in operative position when 15 mounted on a vehicle.

With these and other objects in view, the invention consists of certain novel features of construction, as will be more fully described, and particularly pointed out in the 20 appended claim.

In the accompanying drawings:

Figure 1 is a front view illustrating the general appearance of my improved number-plate frame with a number plate 25 mounted therein.

Figure 2 is a sectional side elevation on line 2—2 of Figure 1, illustrating the number plate as mounted in a frame, the latter secured in position on the supporting 30 bracket.

Figure 3 is an enlarged view showing a portion of the number plate.

Figure 4 is a section on line 4—4 of Figure 3, showing the general shape of the 35 frame in section.

Figure 5 is a section on line 5—5 of Figure 3, illustrating the inwardly-extending tab and the enlarged bearing surface provided by the tab for the support of the 40 thin number plate also as a convenient means in which the plate may be secured to the supporting bracket.

With reference to the drawings 10 designates my improved form of number plate 45 which is preferably made of cast metal and of sufficient strength to rigidly support the thin metal of the plate on which the registering numbers are carried.

The outer or exposed surface 11 of this 50 frame is preferably in oval or convex form presenting a handsome and attractive appearance from the front of the plate, and the rear of the frame is preferably recessed as at 12 providing a rearwardly extending marginal lip 13 all about the frame.

The inwardly extending or front edge of the frame provides a suitable support as at 14 against which the outer marginal surface of the plate 15 rests.

The rearwardly extending lip or flange 80 13 provides a recess of sufficient depth to not only receive and protect the marginal edges of the number plate but also to receive and house the nuts 16 which are secured to the inner ends of the binding 65 bolts 17.

In order to reinforce and stiffen this frame, I have formed inwardly-extending corner sections 18, the lower corners 18 of which are adapted to provide enlarged portions 70 through which the securing bolts 17 may be passed without weakening the frame.

I have also provided on the upper member of the frame two downwardly extending pads or ears 20 which perform two 75 functions; first, they provide an extended area for suitably supporting the upper edge portion of the number plate; and second, they provide enlarged or stiffening members through which the bolts 21 may be passed 80 through the number plate and also through the bracket member 22 for securing the frame and its plate in position on a vehicle.

My improved number plate is extremely simple and practical in construction and by 85 its use the thin sheet metal number plate may be firmly supported in proper position to withstand the racking and jarring of the rapidly running vehicle; and also by its use the plate may be firmly secured to a vehicle- 90 bracket to be supported in the desired position thereon. Then again by the use of my improved number plate frame the looks of the plate are much improved rendering the whole handsome and attractive in appearance. 95

The foregoing description is directed solely towards the construction illustrated, but I desire it to be understood that I reserve the privilege of resorting to all the 100 mechanical changes to which the device is susceptible, the invention being defined and limited only by the terms of the appended claim.

I claim:

A number-plate frame for motor vehicles, 105 comprising a rectangular frame having its front face oval in cross section and its rear face recessed to a substantial depth to receive and cover both the marginal edges of 110

the number plate and the binding nuts therefor, the upper bar of said frame also having a pair of spaced apart inwardly-projecting tabs providing an extended bearing surface for the plate and also providing stiffened members through which the frame may be secured to a pair of supporting

brackets, said frame also having reinforcing corner portions adapted to also receive the plate-receiving bolts.

10

In testimony whereof I affix my signature.

HERBERT A. THAYER.
